UNITED STATES PATENT OFFICE.

WILLIAM A. BERNARD, OF NEW HAVEN, CONNECTICUT, ASSIGNOR TO THE WILLIAM SCHOLIHORN COMPANY, OF NEW HAVEN, CONNECTICUT.

HAND TOOL.

Application filed April 4, 1921. Serial No. 458,223.

This invention relates to hand tools and more particularly to a nail setting tool which is adapted to position and drive a nail in relatively inaccessible places where it is difficult or impossible to use a hammer or other tool for this purpose. While my improved tool may be found particularly useful by cobblers in the driving of nails in the heels of shoes where it is difficult to position the nail with the fingers and drive it by the ordinary cobbler's hammer, it will be obvious that my improvements will be of broader application and that such a tool as I have provided may be found desirable in driving a nail in any place which is relatively inaccessible.

One object of my invention is to provide a tool of the character described by which a nail may be positioned and driven in a location otherwise inaccessible.

Another object of my invention is the provision of a tool which will have in combination means for positioning the nail where it is desired to drive the same and means to drive it into the work.

A still further object of my invention is to provide a tool of the class described having jaws which will support a nail in upright position, so that it need not be held by the fingers while being driven and which are yieldably expandable to release the nail when the same is driven into the work.

A still further object of my invention is to provide a tool with a hollow end portion into which a nail may be inserted, so that it will project from the end of the tool, but will be yieldably retained therein by contact of the jaws of the tool with the enlarged end or head of the nail, the jaws spreading when the nail is driven between them by a driving plunger which forms a part of my improved tool.

To these and other ends the invention consists in the novel features and combinations of parts to be hereinafter described and claimed.

In the accompanying drawings:

Fig. 1 is a side elevational view of a nail setting tool embodying my improvements; Fig. 2 is a longitudinal sectional view of

the same showing the driving plunger in raised position;

Fig. 3 is a view similar to Fig. 2 showing the driving plunger in its lowered position and a nail which has been completely driven into the work thereby;

Fig. 4 is a transverse sectional view on the line 4—4 of Fig. 2;

Fig. 5 is a transverse sectional view on line 5—5 of Fig. 2; and

Figs. 6 and 7 are detail longitudinal sectional views of the lower end portion of the tool showing a nail supported in different positions therein.

Although it will be obvious that the principles of my invention may be embodied in means other than those shown, I have chosen to illustrate a preferred form of my invention as embodying an elongated body member 10, which is provided with a longitudinal opening or bore 11 extending entirely therethrough. Although the shape of this body member is not an important feature of the invention and may be varied as desired, it may be stated that, as shown, the body member is of cylindrical form and the bore 11 therein is likewise of the same form. A longitudinal slot or opening 12 is provided through the wall of the body member 10, the purpose of which will be explained hereinafter.

The nail driving means which I have represented in the drawing consists of a plunger 13 of suitable material such as cold rolled steel or the like, which is provided at its upper end with a knob 14 or the like by which it may be operated. The driving plunger 10 has set into one side thereof a set screw 15, the head of which projects into the slotted opening 12 and thus guides the driving plunger in its movement. It will be obvious that as shown in Fig. 2 the upward movement of the plunger will be limited by the contact of this screw with the upper end of the longitudinal slot 12 so that it will not be possible to inadvertently withdraw the plunger from the body of the tool when raising it preparatory to delivering the blow upon the nail. The lower end of the driving plunger 13 is somewhat reduced,

as shown at 16, and is provided with a punch member 17 which may be made of hard steel or some wear resisting material. While this member may be formed integral with the 5 punch itself, it is preferred to make it in a separate piece machined to fit in a socket 18 provided in the lower end of the plunger. The punch member may be driven into its 10 socket and will be tightly retained therein during the operation of the tool. When made in this manner, it will be seen that if the punch member becomes worn or broken, it may be pulled or bored out and a new one 15 provided in its place.

15 To the lower end of the body portion 10 is secured a tip portion 19, which is provided with a longitudinal bore 20 which forms a continuation of the bore 11. The bore 20 is reduced at its lower end, as shown 20 at 21, until it is in cross sectional area approximately equal to the head of the nail or tack which is intended to be driven by the tool. The lower tip end of the portion 19 is provided with a small opening 22, 25 which is in communication with the bore 21 and permits the body of the nail when placed within the bore to project from the lower end of the tool, as shown in Fig. 6. The tip 19 is provided with a plurality of 30 cuts or slits 23, which, in this instance, are three in number and which extend upwardly from the opening 22, so that resilient or yieldable jaws 24 are provided to surround and hold the nail. The member 19 may, of 35 course, be formed in one piece with the body member 10, as it is secured rigidly thereto, but I have preferred to show this member as formed separately and provided with a threaded upper end which will engage with corresponding threads formed at 40 the lower portion of the bore 11. It is seen that the openings or bores 11, 20 and 21 are all in alignment with each other and extend through the body of the tool which is 45 open at both ends, the lower opening 22 permitting the passage of the nail therethrough when the yieldable jaws spread to permit such passage and the upper opening 50 permitting the operation of the driving plunger therethrough. The member 19 may be made of any suitable material which 55 may be tempered so that resilient jaws may be provided by the cuts or slits 23. At 25 I have shown a nail in different position in relation to the tool and the work 26 into which the nail is to be driven. As shown the "work" consists of the heel of a lady's shoe, which is usually secured by relatively 60 long nails of the type shown.

65 The operation of my device is as follows: As shown in dotted lines in Fig. 2, a nail which is intended to be driven by the tool is inserted through the slot 12 into the bore 11 of the tool. The nail slips down immediately to the position shown in Fig. 6 as the

yieldable jaws are usually sufficiently spread to permit the body of the nail to pass through the opening 22 the jaws retaining it by means of the enlarged head at the upper end. The tool is then placed upon the 70 work at the point at which it is desired to drive the nail, the nail being pushed upwardly within the tool again by contact with the work and held in a vertical position therein, as shown in Fig. 7. The tool 75 is now in position to deliver a stroke upon the nail to drive it into the heel of the shoe. In Fig. 1, the nail is shown as partially driven into the shoe and the plunger being withdrawn upwardly for another stroke, 80 while in Fig. 3 the nail is shown as completely driven into the work and the plunger, as shown, is sufficiently long so that the driving punch member extends 85 down between the jaws and in contact with the enlarged head of the nail after it has been expelled from the jaws of the tool. As shown in that figure, these jaws not only spread to allow the passage of the head of the nail therethrough, but also to permit the 90 passage of a short length of the punch member 17.

95 While I have shown and described a preferred form of my invention, it will be understood that I am not to be limited to the details shown, but that the same is capable of various modifications and modifications which will fall within the spirit of the invention and within the scope of the 100 appended claims.

105 What I claim is:

1. A one piece hollow tip for a nail driving tool or the like having a solid upper portion adapted to be secured to a driving mechanism and a slit springable lower portion, said lower portion being provided with a bore slightly larger in diameter than the body of the nail to be driven, whereby the nail is retained within the tip, and a second bore extending from the first mentioned 110 bore upwardly substantially the length of the nail and of a diameter slightly larger than the head of the nail wherein the nail is supported in a vertical position.

115 2. A tip or nail box for a nail driving tool having a non-resilient upper portion and a resiliently jawed lower portion, said jaw portion having a bore in the end thereof of a diameter slightly larger than the nail body, a bore connecting therewith slightly larger in diameter than the nail head and a bore in the upper end of the jaw portion continuing through the non-resilient portion of the tip of still larger 120 diameter.

125 3. In a nail driving tool or the like, means to retain a nail therein during the driving operation, including a springable jawed member provided with a bore in the lowermost end thereof, slightly larger in diam- 130

eter than the body of the nail to be driven, a bore above and concentric with said first mentioned bore, adapted to slidely receive the driving plunger of said tool, and a bore intermediate said first and second mentioned bores in connection with and concentric to both, said intermediate bore being of a diameter slightly larger than

the head of the nail to be driven wherein the nail is supported substantially in alignment and concentric to the driving plunger of said tool. 10

In witness whereof, I have hereunto set my hand on the 2nd day of April, 1921.

WILLIAM A. BERNARD.
